Primary Examiner — Mitchell I. Siegel

(57) CLAIM

The ornamental design for a universal golf shaft adapter, as shown and described.

DESCRIPTION

FIG. 1 is a Front elevational view of a universal golf shaft adapter showing my new design;

FIG. 2 is a Rear elevational view thereof;

FIG. 3 is a Left side view thereof;

FIG. 4 is a Right side view thereof;

FIG. 5 is a Top plan view thereof;

FIG. 6 is a Bottom plan view thereof;

FIG. 7 is a Perspective view thereof; and,

FIG. 8 is another perspective view thereof.

1 Claim, 8 Drawing Sheets
